FIG. 3.

INVENTOR

Albert M. Knapp

UNITED STATES PATENT OFFICE.

ALBERT M. KNAPP, OF PROVIDENCE, RHODE ISLAND.

SYRINGE.

SPECIFICATION forming part of Letters Patent No. 397,060, dated January 29, 1889.

Application filed September 25, 1885. Serial No. 178,131. (No model.)

To all whom it may concern:

Be it known that I, ALBERT M. KNAPP, of the city of Providence, in the county of Providence, State of Rhode Island, have invented 5 a new Syringe-Pipe, of which the following is a specification.

My invention consists in an improved syringe-pipe, to be used in connection with a syringe for the purpose of making liquid applications to the internal surface of the vagina 10 and neck of the womb for the medical treatment of those parts.

The vagina rests in rugae or folds; consequently unless expanded a considerable portion 15 of its surface is not reached by medicated liquids injected through the small tubes now in general use. Through the operation of my improved device a degree of expansion is secured, exposing the whole vaginal surface and 20 neck of the womb to the influence of medical washes, and also plugging the vaginal canal, thereby retaining the liquids in contact with the parts for a proper length of time—a desirable object in the treatment.

25 In the accompanying drawings, which illustrate my invention, Figure 1 represents a side elevation of my improved device as it is when not in use, the expansible bulb being closed. Fig. 2 is a sectional view, the bulb being in the 30 position assumed by it when in use. Fig. 3 is a detail view of the valve adapted to the end of the pipe.

To the free extremity of a syringe-pipe, *h*, or tube, quite close to the end *b*, is attached 35 an expansible thin hollow bulb, *a*, the opposite sides of which are fastened air-tight to said tube or cylinder, which passes through said bulb and projects slightly beyond, as at *b*. The continuation of the canal or bore *e* through 40 said tube is partially interrupted in that portion covered by said bulb and freely communicates with the interior of the same, as shown by the arrows, Fig. 2. On the end of said tube, and in close proximity to said bulb, a 45 valve, *k*, is attached, which offers a slight resistance to the passage of liquids forced into the opposite end, *c*. Through the means of the obstruction secured by this valve liquids injected into said tube must fill said ex- 50 pansible bulb to its full capacity before pressure enough is brought to bear upon said valve to open the same and give vent to the in-

jected solutions. The expansion of said bulb *a* can also be accomplished in the following manner: In the end *b* of the said tube, which 55 extends just beyond said bulb, fine perforations are made. These holes are so small that the liquids forced into said tube cannot be discharged with equal rapidity; consequently they are forced into and continue to expand 60 said bulb so long as the syringe is in operation.

The valve *k* may be used with the fine perforations in the pipe end, and in any event it acts to retard the flow of fluid through the 65 pipe and to prevent its return after it has passed into the vaginal canal.

Operation: Connect the syringe-pipe with the syringe and insert into the vagina so that the said bulb occupies a position just within 70 the vaginal orifice. Operate the syringe, and the solutions will pass through the said tube into the said bulb, filling the same to its greatest capacity, thus separating and expanding the walls of the vagina in the immediate vicinity. The liquids are then forced through 75 said valve, or the said fine perforations, into the vaginal canal. Said expanded bulb plugs the vagina; consequently a quantity of the injected solutions is retained, occupying a 80 space between the surface of said expanded bulb and the mouth of the womb, dilating the vagina to a degree equal to the diameter of said bulb before any of the solution is discharged.

In the operation of the said device, owing 85 to the expansion of said bulb, the instrument has a tendency to press inwardly against the womb. To prevent this, a guard is adjusted to said pipe between said bulb and the point 90 of connection with the syringe.

The instrument is removed from the vagina by disconnecting it from the syringe. The natural contraction of the parts soon discharges the contents of the said bulb, when it 95 is easily displaced.

I am aware that it is old to use a flexible and expansible bulb combined with a vaginal syringe-pipe, and I do not claim this combination, broadly.

I claim as my invention and desire to secure by Letters Patent—

1. In a vaginal syringe, and in combination, the cylinder *h*, having a passage throughout

its length and opening into the vagina at its inner end to receive and conduct the fluid, said cylinder having its sides formed with an opening, and an expansible bulb secured directly on said cylinder at a point between its two ends and about said opening, and having direct communication with the channel through the cylinder, substantially as described.

10 2. In combination, the syringe-pipe *h*, hav-

ing a passage therethrough and openings in its sides, the bulb *a*, secured about said openings and communicating directly with the interior passage, *e*, and the valve *k*, placed over the discharge end of the pipe, substantially as described. 15

ALBERT M. KNAPP.
